UNITED STATES PATENT OFFICE.

JOSEPH BOERO, OF NEW YORK, N. Y., ASSIGNOR TO STEDMAN'S FOUNDRY & MACHINE WORKS, OF AURORA, INDIANA, A CORPORATION OF INDIANA.

PULVERIZER.

1,120,251

Specification of Letters Patent. Patented Mar. 2, 1915.

Application filed March 3, 1914. Serial No. 822,191.

all whom it may concern:

Be it known that I, JOSEPH BOERO, a citizen of France, and residing at 219 West Eighty-first street, New York, in the county 5 of New York and State of New York, have invented a new and Improved Pulverizer, of which the following specification is a full disclosure.

My invention relates to pulverizers, for 10 crushing or grinding dry material, such as hard ores or composite material.

An object of my invention is to provide a pulverizer with a circumferential crushing abutment surface, against which the material 15 is impinged by a series of planetary hammers, each rotatably mounted upon swinging arms radially extended in a circumferential series from a common rotative member, whereby the hammers have a planetary compound motion, rotatively about a common 20 axis; about an individual axis, and oscillatory individually eccentrically to its orbit.

Another object of my invention is to provide a pulverizer with swinging planetary 25 hammers pivotally mounted in an interchangeable fulcrum bearing for adjusting the same radially toward and from a normal axis.

Another object of my invention is to provide a pulverizer with planetary circumferential hammers adapted in their rotation to impinge the material against a circumferential surface, having a portion thereof of 30 grid formation.

Another object of my invention is to provide a grid for a pulverizer, as comprising a series of plates arranged and unitarily combined in relatively spaced parallelism, presenting a circumferential area, and as a 35 unit removably supported within the machine.

Other objects and features of my invention will be in part obvious from the illustration disclosure of the annexed drawings and from 45 the following description thereof, and in such drawings like characters of reference denote corresponding parts throughout all the views, of which:

Figure 1 is a central vertical section of the 50 pulverizer; and Fig. 2 is a section on line 2—2, Fig. 1.

The casing of the machine is of sectional form, offering convenience in assembling and accessibility for renewal of worn or 55 broken parts. The lower portion or base 1

interiorly supports the screen or grid 2, presenting a circumferential grinding surface, toward which the rotary beaters are directed. The preferred construction of screen or grid is as illustrated, and comprises a feature of 60 this invention. It is composed of a plural series of sector plates opposingly arranged upon opposite sides of a central cross bar support, and unitarily provide a semi-circular base grinding surface. Each sector-plate 65 5 of each series has a lateral extension at its upper end adapted to rest upon a ledge 7 projected from the inner surface of the side-wall of the base 1. The opposite end of each plate has an ear extension 8 socketed within 70 a coincidentally shaped surface or seat in the cross bar support 9 secured or bolted to the end walls of the base 1. The plates of each series are secured together transversely by the bolts 10 which pass through the extensions thereof, and the plates relatively spaced by the intervening washers 11, which provide the proper screen-mesh. The upper portion of the casing forms a hopper 12 for receiving the material and directing it toward the revolving beaters or hammers which traverse over the circumferential crushing abutment surface and grid-plates within the casing. Lining-plates 13 are provided having a circumferential surface concentric with the axis of the beaters within the body 14 of the casing and in radii alignment with the grid-surface. The walls of the hopper are also provided with lining plates 15 to reinforce the casing and which 85 are readily renewable and relieve the casing of the wear the employment of the lining plates in the practice is well-known in the art.

The base 1 has its end walls provided with 90 bracket extensions 16 projecting exteriorly beyond the casing and from opposing sides for supporting the bearing-blocks 17, 18, for journaling and supporting the shaft 19 extended through the casing. A pulley 20 is 100 fixed to one end of the shaft, while the opposite end projects from the bearing sufficiently to receive a fly-wheel 21 as a counter-balance and of utility when the material fed into the machine is very irregular in size. 105

22, 23 represent beater or hammer supporting disks splined upon the shaft 19 within the casing, each having a hub extension upon each side thereof with the outer ends of each projected into the casing pro- 110

tecting the shaft, and provide a seal against the escape of dust or pulverulent material. The disks are separated from each other by the split spacing sleeve 24 splined to the 5 shaft 19. Each disk has a series of arms or radial extensions 25 pivotally supported thereon arranged in diametric pairs, and provide bearings for supporting and loosely journaling a roller or cylindrical hammer 26. 10 Each arm 25 has a lateral stud-extension 27 fulcrumed in a polygonally sided adjusting or bearing block 28, as illustrated of octagonal form, seated within a correspondingly shaped aperture in the disk, with its fulcrum 15 bore eccentric to the contour of the block. This provides definite adjustment for the arms radially toward and from the hammer or beater crushing circumferential surface, and provides a self-contained lock for securely 20 mounting the block upon the disk. The free end of each stud is screw-threaded for engaging the nut and washer, to clamp the adjusting block and arm against lateral displacement. 25 From the foregoing description it will be apparent that the hammers or beaters have an oscillating action upon the rapidly revolving disk, eccentric to their normal axis and by centrifugal force are directed radially to a diametric line of said disks. The impact of the hammer blow upon the material deposited against the rearward wall α initially crushes the material so that the heavier particles are reduced before the material 30 is advanced by the beaters or hammers to receive an attrition action by the impingement of the material between the hammers and circumferential wall of the casing. The hammers being pivotally mounted are by 35 centrifugal force normally directed toward a diametric line with the axis of rotation, to reduce the material in the hopper by percussive force, with the hammers yielding to the impact, and escape the larger particles 40 and subject the same to successive percussive action. From the hopper the material is carried by the hammers to be further treated by attrition and percussion in the impingement of the material between the hammers 45 and circumferential grinding abutment surface. The material is subjected to further crushing or pulverizing actions by the planetary disposition of the hammers, whereby the hammers in the nature of rollers 50 are free to revolve, producing a compound action upon the material, that of crushing and grinding, more rapidly disintegrating the material, decreasing the yielding tendency of the hammers, and also increasing the attrition area to that of the circumference of each roll. The provision of 55 planetary hammers is also quite a factor toward increasing their life, for the hammers circumferentially present a large area constantly mobile whereby the wear is not con-

fined to any one point or position. The definite radial adjustment of the fulcrum of the hammers provides an accommodation for wear, and a regulation for different grindings, with a further advantage of providing renewable fulcrum bearings, reducing maintenance cost. 70

By way of further elaboration, it may be recognized that the machine evolves a new process of pulverization by reason of its 75 mechanical construction. The hammers or beaters during a portion of their cycle lose their identity as such and appropriately may be defined as planetary rollers. Each roller is longitudinally coextensive approximately of the encompassing grinding surface coaxially, with an intervening clearance between the roller-supporting arms 25, roller and main shaft, so that the rotor as a unit is largely dispossessed of conveyer characteristics, except in so far as is due to its high centrifugal velocity. This enables the material within the concave or partially circumferential grinding surface to be progressively distributed from one roller to another. The material is therefore subjected to the action of a multiplicity of planetary grinding or abrasion surfaces. 80

The high velocity of the rotor centrifugally projects the arms and rollers radially, each in a diametric line with the main axis, and at a degree of pressure greater than any sustaining weight of material within the transitory trough formed by the concave and a roller. Each roller in its cycle within the concave is mobile, producing a compound grinding action, and yields or swings to any impact occasioned by an obstructing deposit of material in the trough. As each roller advances in its cycle to the open gap in the concave at the hopper, it serves as means to forcibly project the material against or toward the vertical wall or abutment α , which extends in a plane coincident with and interveningly between parallel tangent and diametric lines of the concave, or coincident with a chord line of the concave, against which the material is initially crushed by percussion. 100

The junction of the vertical lining wall and concave provides a shoulder β , against which the material is crushed by a hammer action of the rollers, which at such point may be recognized as beaters with the hammers yielding to any impact to escape the material. Thus each swingingly mounted planetary roller successively functions to crush the material by projection, disintegration and attrition, producing a pulverizer of increased efficiency, durability, and with the wear of the hammers reduced to a minimum. Each hammer or roller is coextensive of the grinding surface longitudinally, which produces a hammer of increased weight, which also is quite a factor in the pulverizer. 110 115 120 125 130

It is obvious and comprehended within the scope of this invention that the hammers or beaters may have a roughened circumferential surface, instead of the smooth type disclosed in the drawings, in fact, their contour may be variously shaped to enhance their utility in pulverizing or reducing different kind and quality of material. The precept herein having primary reference to 10 the broadest aspect of the invention, that of providing planetary hammers with their configuration optional. Each unitary series of said plates is shown as abutting a transverse plate 30 resting upon the ledge 7 15 of the base end walls, and adjustable horizontally by the set-screw 29, whereby the abutment surface of the grid as a unit can be alined with the circumferential surface of the lining plates 13. The edge or end of 20 each grid plate is curved and is adapted to bind with the end of the lining plate as the grid is adjusted by the plate 28 swinging on the cross bar 9 as a fulcrum.

Having thus described my invention I 25 claim as new and desire to secure by Letters Patent of the United States:—

1. A machine of the class described comprising in combination an annular casing providing a circumferential crushing abutment surface, a rotary member having a pair of radial extensions, and a crusher independently rotatably mounted between the ends of said extensions, longitudinally approximately coextensive of said crushing 35 surface and in a plane parallel therewith.

2. A machine of the nature described, combining a casing interiorly having a partly circumferential grinding surface, and an abutment surface extended from one end of said circumferential surface coincident 40 with a chord line thereof to provide a crusher shoulder at the juncture of said surfaces, a rotary member having a series of swinging radial arms arranged in pairs oppositely, a hammer independently rotatively 45 mounted between the ends of each pair of radial arms longitudinally approximately coextensive of said grinding surface and in a plane parallel therewith.

3. A machine of the nature described, 50 combining a casing interiorly having a partly circumferential grinding surface, and an abutment surface extended from one end of said circumferential surface coincident with a chord line thereof to provide a 55 crusher shoulder at the juncture of said surfaces, and a series of swinging planetary hammers within said circumferential surface revoluble about a common axis, each axially approximately coextensive of said surface 60 and independently rotative about its own axis.

In witness whereof, I hereunto subscribe my name, as attested by the two subscribing witnesses.

JOSEPH BOERO.
